CLAIM

The ornamental design for an accessory for supporting mobile devices and displaying information, as shown and described.

DESCRIPTION

FIG. 1 is a front view of a first embodiment of an accessory for supporting mobile devices and displaying information showing the new design.

FIG. 2 is a front view of the first embodiment of the accessory for supporting mobile devices and displaying information showing a screen in a folded position.

FIG. 3 is a rear view of the first embodiment of the accessory for supporting mobile devices and displaying information showing the screen in an open position.

FIG. 4 is a rear view of the first embodiment of the accessory for supporting mobile devices and displaying information showing the screen in a folded position.

FIG. 5 is a top perspective view of the first embodiment of the accessory for supporting mobile devices and displaying information showing the screen in an open position and a recess on a supporting surface.

FIG. 6 is a top perspective view of the first embodiment of the accessory for supporting mobile devices and displaying information showing the screen in a folded position.

FIG. 7 is a bottom perspective view of the first embodiment of the accessory for supporting mobile devices and displaying information showing the screen in an open position;

FIG. 8 is a bottom perspective view of the first embodiment of an accessory for supporting mobile devices and displaying information showing the screen in a folded position.

(Continued)

FIG. 9 is a front view of a second embodiment of an accessory for supporting mobile devices and displaying information showing the new design.

FIG. 10 is a front view of the second embodiment of the accessory for supporting mobile devices and displaying information showing a screen in a folded position;

FIG. 11 is a rear view of the second embodiment of the accessory for supporting mobile devices and displaying information showing the screen in an open position.

FIG. 12 is a rear view of the second embodiment of the accessory for supporting mobile devices and displaying information showing the screen in a folded position.

FIG. 13 is a top perspective view of the second embodiment of the accessory for supporting mobile devices and displaying information showing the screen in an open position.

FIG. 14 is a top perspective view of the second embodiment of the accessory for supporting mobile devices and displaying information showing the screen in a folded position.

FIG. 15 is a bottom perspective view of the second embodiment of the accessory for supporting mobile devices and displaying information showing the screen in an open position; and,

FIG. 16 is a bottom perspective view of the second embodiment of the accessory for supporting mobile devices and displaying information showing the screen in a folded position.
